UNITED STATES PATENT OFFICE.

CARL STRAUSS, OF NEW YORK, N. Y.

SCARF-FASTENER.

SPECIFICATION forming part of Letters Patent No. 402,868, dated May 7, 1889.

Application filed January 7, 1889. Serial No. 295,657. (No model.)

To all whom it may concern:

Be it known that I, CARL STRAUSS, of the city, county, and State of New York, have invented a new and useful Improvement in 5 Scarf-Fasteners, of which the following is a full, clear, and exact description.

This invention relates to gentlemen's neck-scarfs designed to cover a portion of the shirt-bosom left exposed by the vest of the wearer, 10 and which have had permanently attached to one of their tying ends or tabs a retaining device or clamp for preventing the scarf from riding up or getting out of place; and the invention consists in the combination, with the 15 scarf, of a permanently-attached spring-clamp or retaining device of peculiar construction and adapted to engage with the shirt-bosom of the wearer, substantially as hereinafter described, and pointed out in the claim.

Reference is to be had to the accompanying drawings, forming a part of this specification, in which similar letters of reference indicate corresponding parts in all the figures.

Figure 1 represents a view in perspective of 25 a gentleman's scarf with an attached fastening applied to the inner face of the tying end of the scarf in accordance with my invention, said fastening being shown as thrown open; Fig. 2, an inner face view of the tying end 30 portion of the scarf in part, with the fastening seen in its closed position applied. Fig. 3 is a transverse section upon the line $\alpha\alpha$ in Fig. 2; Fig. 4, a view in perspective of the fastener detached, and Fig. 5 a view of an individual 35 with scarf applied and the latter secured in position by the fastener.

A indicates the main portion of the scarf, and b the tying end portion thereof, which, after being passed around the neck of the 40 wearer and through the knot or loop-like portion c, it is necessary to secure below to prevent the scarf from riding up or getting out of place. For this purpose I permanently at-

tach to the lower part of the tying end portion b of the scarf a spring-clamp fastener, B, 45 which is adapted to engage with the bosom of the shirt—as, for instance, by constructing said fastener with a bent tongue, d, which may or may not be roughened or toothed on its inner surface, as shown at e, Fig. 4, and 50 which is pivoted to work in lugs f f upon a slotted spring-plate, g, through which a lip on the back end of the tongue passes and bears against a base-plate, h. This base-plate has the ends of the spring-plate g riveted to it, 55 and the same is constructed with an enlarged spread flat portion, k, having a series of perforations, s, in it to provide for stitching—as by thread, i, in Figs. 1 and 3—the spring-clamp to the scarf. The whole of the clamp, except 60 the tongue d, may be concealed within the scarf.

The tongue is held closed by the spring-plate g and is opened against the tension of the spring. The whole clamp, being of a flat 65 construction, forms no objectionable protuberance, is cheap, and may be easily attached to the scarf by stitching, and when once secured to the scarf never requires to be removed, but will always be an appendage to 70 the scarf ready for use.

Having thus described my invention, what I claim as new, and desire to secure by Letters Patent, is—

The spring-clamp B, consisting of the piv- 75 oted tongue d, slotted spring-plate g, and the base-plate h, having a spread flat portion, k, provided with stitching-perforations s, in combination with the scarf to which it is attached, substantially as herein shown and described, 80 and for the purpose specified.

CARL STRAUSS.
